United States Patent Office.

AMES VAN WART, OF NEW YORK, N. Y.

Design No. 4,490, dated November 22, 1870.

DESIGN FOR STATUARY.

The Schedule referred to in these Letters Patent and making part of the same.

To all whom it may concern:

Be it known that I, AMES VAN WART, of the city of New York, in the county and State of New York, have invented a new and original Design for Statuary; and I do hereby declare that the following is a full, clear, and exact description thereof, which will enable others skilled in the art to make and use the same, reference being had to the accompanying photograph forming part of this specification.

The photograph represents a front view of my new design for statuary.

This invention relates to a new design for a group of statuary, and consists in the representation of two kittens resting on a pillow, one being represented

asleep, and the other awake. The sleeping animal is stretched upon the pillow; the other rests its head on the back of the companion and appears to use the ears for outward vigilance, while the eyes indicate a state of deep meditation.

I claim as my invention—

The design for statuary herein described.

The above specification of my invention signed by me this 25th day of October, 1870.

AMES VAN WART.
